ELECTRIC LIGHTING FIXTURE

Filed May 28, 1927

UNITED STATES PATENT OFFICE.

ADOLPH C. RECKER, OF OAKVILLE, CONNECTICUT, ASSIGNOR TO CHASE COMPANIES, INC., OF WATERBURY, CONNECTICUT, A CORPORATION.

ELECTRIC-LIGHTING FIXTURE.

Application filed May 28, 1927. Serial No. 194,903.

My invention relates to an improvement in electric lighting-fixtures, the object being to provide convenient and reliable means for mounting standard pull-chain electric-light 5 sockets in canopies, whether designed for ceiling or side-walls.

With these ends in view, my invention consists in an electric lighting-fixture characterized by a canopy having a fixed 10 concentric mounting-sleeve provided with a bayonet-slot for the reception of the chain-guide of a standard pull-chain electric-light socket, and a collar applied to the said sleeve over the said slot.

My invention further consists in an electric lighting-fixture characterized as above and having certain details of construction and combinations of parts as will be hereinafter described and particularly pointed 20 out in the claim.

In the accompanying drawings:

Fig. 1 is a view in side elevation of an electric lighting-fixture constructed in accordance with my invention;

Fig. 2 is a broken view in vertical central section thereof on an enlarged scale;

Fig. 3 is a corresponding view, taken at a right angle to Fig. 2, and showing the sleeve and its cap in elevation;

Fig. 4 is a view corresponding to Fig. 3 but showing the socket-casing and the friction-collar of the sleeve removed;

Fig. 5 is a detached perspective view of the friction-collar of the sleeve.

In carrying out my invention, as herein shown, in Figs. 1 to 5 inclusive, I form a bayonet-slot 10 in the side-wall of a fixed mounting-sleeve 11 arranged concentrically within the lower portion of a canopy 12 of any approved form and construction, the lower end of the said sleeve being shaped, as shown, to form an inwardly-projecting seating-shoulder 13, upon which the shoulder 14 of a standard pull-chain electric-light socket-casing 15 is brought to a bearing. Directly below the seating-shoulder 13, the said sleeve is shaped to form an outwardly-projecting bead 16 which rests upon the inwardly-turned lip 17 of the canopy, the extreme lower edge 18 of which is turned outwardly to grip the inwardly-turned upper edge 19 of a shade-holder 20, which may also be of any approved form and construction. The extreme lower edge 21 of 55 the sleeve 11 is bent outwardly under the

edge 18 aforesaid, whereby the said sleeve is firmly installed within the canopy 12 as a unit with the same and the shade-holder 20. However, I wish it understood that my invention is not limited to the specific 60 manner described of rigidly installing the mounting-sleeve 11 within a canopy of an electric lighting-fixture.

The bayonet-slot 10 aforesaid receives the bell-shaped chain-guide 22 forming a feature of the standard pull-chain electric-light socket-casing 15 and receiving and guiding the bead pull-chain 23 thereof. The upper wall 24 of the horizontal reach of the bayonet-slot 10 co-acts with the upper 70 edge of the bell-shaped chain-guide 22 to prevent the upward displacement of the socket-casing 15 in the sleeve 11, while the end-wall 25 of the horizontal reach of the said bayonet-slot prevents the counter-clockwise rotary movement of the casing in the sleeve. For preventing the clockwise rotary movement of the casing in the sleeve, I employ a collar 26 preferably adapted to fit snugly over the upper end of the sleeve 11, 80 and formed in its lower edge with a locking-notch 27 which fits over the upper portion of the said chain-guide 22, as clearly shown in Fig. 3 one wall of the said notch 27 engaging with one side of the chain-guide 22 85 to prevent the socket-casing from turning in one direction within the mounting-sleeve 11. The said collar is formed at its upper end with an inwardly-turned annular stop-flange 28 which bears directly upon the upper edge of the shoulder 29 of the cap 30 of the socket-casing 15. To prevent the clockwise rotation of the collar 26 upon the sleeve 11, the collar is indented, as at 31, to form 90 an abutment-edge 32 which engages with the outer side-wall 33 of the vertical reach of the bayonet-slot 10.

Under my invention, it becomes very convenient to install a standard pull-chain socket-casing in a canopy, in which it is 100 firmly held against endwise or rotary displacement.

While I have illustrated and described my invention as applied to a ceiling canopy, it is equally applicable to a canopy designed 105 for use in other locations, as on a side-wall.

I claim:

An electric lighting fixture, comprising a canopy, a fixed mounting-sleeve concentrically installed therein, a bayonet-slot open- 110

ing from the upper edge of the said sleeve for the reception of the pull-chain guide of a standard electric-light socket-casing, the said guide co-acting with the inner wall of the horizontal reach of the said slot to prevent the turning of the casing in the sleeve in one direction, a collar applied to the upper end of the said sleeve, a locking-notch formed in the lower edge of the said collar 10 to fit over the said guide to prevent the

socket-casing from turning in the opposite direction with respect to the said sleeve, and an abutment struck inward from the collar to engage the outer wall of the vertical reach of the said slot to prevent the collar 15 from turning on the sleeve away from the horizontal reach of the said bayonet-slot.

In testimony whereof, I have signed this specification.

ADOLPH C. RECKER.
